CLAIM

The ornamental design for the eyecup, as shown and described.

DESCRIPTION

FIG. 1 is a front elevational view of an eyecup showing may new design;

FIG. 2 is a left side elevational view thereof;

FIG. 3 is a top plan view thereof, the bottom view being a mirror image of the top plan view shown;

FIG. 4 is a right side elevational view thereof;

FIG. 5 is a right side elevational view thereof;

FIG. 6 is a sectional view thereof taken along line 6—6 of FIG. 1;

FIG. 7 is a sectional view thereof taken along line 7-7 of FIG. 1;

FIG. 8 is a perspective view thereof;

FIG. 9 is a reference perspective view of the eyecup in use; and,

FIG. 10 is a reference perspective view of the eyecup fitted with a rubber member.

The broken lines showing of the strap and rubber members in FIGS. 9 and 10 are for illustrative purposes only and form no part of the claimed design.
